UNITED STATES PATENT OFFICE.

AUGUST BUERMANN, OF NEWARK, NEW JERSEY.

DESIGN FOR A PATTERN FOR SPURS.

SPECIFICATION forming part of Design No. 16,767, dated July 6, 1886.

Application filed January 25, 1886. Serial No. 189,706. Term of patent 14 years.

To all whom it may concern:

Be it known that I, AUGUST BUERMANN, a citizen of the United States, residing at Newark, in the county of Essex and State of New Jersey, have invented and produced a new and original Design for Patterns for Spurs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the drawings, Figure 1 is a plan of a pattern. Fig. 2 is a side elevation of the same. Fig. 3 is a sectional view taken through line *y*. Fig. 4 is a sectional view taken through line *x*. Fig. 5 is a section through line *y'*, and Fig. 6 a section through line *y''*; these several views being deemed sufficient to illustrate the invention.

The leading feature of the design consists in the spur-pattern, in which the heel-band portion is transversely ribbed at a point beneath the rowel-arm, the rib being angular in cross-section and rounded off at the lower edge of the said heel-band.

It consists, further, in the general configuration of the pattern, substantially as will be hereinafter set forth.

In said drawings, *a* is the heel-band portion of the spur-pattern, the outer face of which is rounded, as shown in Figs. 2 and 3, and from the point of union with the rowel-arm

the ends or extensions *b b* of the band taper or are contracted toward the extremities *c c*, at which they are rounded when viewed in side elevation, as in Fig. 2. At the center of the band, immediately beneath the rowel-arm, the band is ribbed transversely, the rib appearing to be an extension of the rowel-arm. Said rib is angular, as indicated in Fig. 6, and at its lowest end is rounded, as at *f*. The rowel-arm *d* is angular, being nearly square in section through line *y'*, as indicated in Fig. 5. Above the upper line of the heel-band the said rowel-arm curves upwardly and outwardly from said band, and at the extremity is enlarged or head-shaped in side elevation and rounded, as at *g*. In plan the said extremity is bifurcated, as in Fig. 1.

What I claim as new is—

The design for a spur-pattern, the same consisting of a spur pattern in which the heel-band is rounded on the outer face and at the extremities and ribbed beneath the rowel-arm, said rib being angular and at the lower end rounded, and the rowel-arm being square in section and head-shaped at its outer end, and curved when viewed in side elevation, substantially as set forth.

In testimony that I claim the foregoing I have hereunto set my hand this 20th day of January, 1886.

AUGUST BUERMANN.
